UNITED STATES PATENT OFFICE

ERNST HURLBRINK, OF BERLIN, GERMANY, ASSIGNOR TO FIRM MARTINI & HÜNEKE
MASCHINENBAU-AKTIEN-GESELLSCHAFT, OF BERLIN, GERMANY

APPARATUS FOR STORING AND DISPENSING LIQUID FUELS

Application filed June 13, 1928, Serial No. 285,083, and in Germany June 18, 1927.

My invention relates to an apparatus for storing and dispensing gasoline, benzol and other liquid fuels and more particularly to an apparatus by which the liquid to be dispensed is driven out of a storing tank by introducing a heavier liquid such as water under pressure into the tank and in which both the conduit for introducing and discharging the fuel and the conduit for introducing and discharging the water is provided in the interior of the tank with a float actuated valve through which the fuel conduit is automatically closed as soon as the contacting plane between the two liquids has reached a predetermined upper level whilst the water conduit is automatically closed as soon as the contacting plane between the two liquids has reached a predetermined lower level.

The float actuated valves used heretofore have the disadvantage that the closing of the conduits only takes place little by little within a longer period just as the contacting plane between the two liquids rises or sinks in the relatively large tank, so that it is very uncertain at which point of time the valve is really closed. Therefore when using the known regulating means it is necessary that the floats are already operative at a level of the contacting plane which is relatively far from the orifices of the fuel conduit and the water conduit so that the volume of the tank is badly utilized. This disadvantage is still increased by the fact that the vertical length of the floats must be relatively large for effecting a sufficient buoyancy of the floats and correspondingly a tight closing of the valves.

The main object of my invention is to avoid the said disadvantages by lodging the floats in relatively small chambers which are open on one side and adapted to be alternatively filled with water and with gasoline whereby the substitution of the one liquid by the other takes place within a very small period in a chamber as soon as the contacting plane between the two liquids reaches the respective chamber. A further object of my invention is that floats of a larger vertical length may be used so that a safe closing of the valve is effected and the volume of the tank is well

utilized. Further objects of my invention will appear hereinafter.

Preferred embodiments of my invention are illustrated in the accompanying drawings.

Fig. 1 is a vertical section through a part of a storage tank provided with the improved automatic valve closing means.

Fig. 2 is a side elevation with parts in section of a float and valve unit provided in the upper part of the storage tank.

Fig. 3 is a side elevation with parts in section of a float and valve unit provided in the lower part of the storage tank, and

Fig. 4 is a horizontal section through the unit shown in Fig. 2.

According to Fig. 1 of the drawings 1 is a tank with which two pipes or conduits 2 and 12 are communicating. The pipe 2 serves for the supply of water under pressure and extends to the lower part of the tank. The orifice 3 of the pipe 2 forms a valve seat which is open on its upper side. Above said orifice a chamber 4 is arranged having the shape of an inverted pot which is correspondingly open on its lower side. The chamber 4 is connected with the pipe 2 by means of bridges 4^a. The upper wall 6 of the chamber forms a return valve which allows liquid to flow out but not to enter into the chamber at its upper side. The valve 6 is covered by a hood 9 which limits the stroke of the valve and prevents any substance being suspended in the liquid to be deposited on the valve. In the chamber 4 the float 7 is lodged which is guided by means of lateral projections 7^a on the walls of the chamber and which carries the valve cone 8 cooperating with the valve seat 3.

The orifice of the fuel pipe 12 communicates with the upper part of the tank 1 and forms a valve seat 13 opening downwardly. The cooperating valve 18 is connected with a float 17 which is guided in the same way as the float 7 in a chamber 14 which is connected by means of bridges 14^a with the water pipe 2. The chamber 14 is open on its upper side at 15 and closed on its lower side by means of a bottom 20. The rim of the bottom is bent upwards and forms in connection with a

flange 21 of the chamber 14 a ring shaped valve seat with which a ring shaped valve 16 cooperates which allows liquid to flow out of the chamber but prevents liquid from entering into the chamber at its lower side. The valve 16 is encased by an extension 19 of the wall of the chamber to prevent soiling of the valve. The specific weight of each of the float aggregates including the float proper, the valve and the valve spindle is smaller than that of water but larger than that of gasoline or another lighter liquid.

The working of the apparatus is as following:

According to the working state illustrated in the drawing half of the contents of the tank 1 consists of fuel A and the other half of water B, so that the contacting plane 10 of the two liquids lies approximately in the middle of the tank. The lower chamber 4 is completely filled with water, the float 7 is raised and the valve 8 is opened, whilst the upper chamber 14 is completely filled up with gasoline. The float 17 is in its lower position and the valve 18 is also opened.

As soon as gasoline is introduced into the tank through the pipe 12 the contacting plane 10 will sink, and by a pressing action water will be ejected through the pipe 2. As long as the contacting plane of the two liquids does not reach the edge 5 of the chamber 4, the said chamber remains filled with water, and the float 7 is accordingly raised and the valve 8 open. But as soon as the contacting plane sinks below the edge 5 of the chamber 4 the water falls out of the chamber which is filled up with gasoline at once. The float 7 moves downwards immediately, and the orifice 3 of the conduit 2 is closed by the valve 8 so that a discharge of gasoline through this conduit is impossible.

As soon as gasoline is taken from the tank through the pipe 12 by introducing into the tank water under pressure through the pipe 2, the contacting plane will be raised. The rising water may flow into the chamber 4 from below, as the rising return valve 6 allows the gasoline to flow out. In correspondence thereto the float 7 is raised and the valve 8 opened. As far as the contacting plane reaches the lower part of the chamber 14 this does not affect the existing conditions as the return valve 16 does not allow water to flow into the chamber which is filled with gasoline, so that the float 17 remains in its lower position. But as soon as the contacting plane has reached the upper edge 15 of the chamber 14, the gasoline in the chamber is at once substituted by the heavier water, so that the float 17 is quickly raised and the orifice 13 of the pipe 12 closed by the valve 18. The further discharge of gasoline is interrupted and a drawing off of the water rendered impossible.

When the tank is newly filled up with gasoline the contacting plane 10 will sink below

the chamber 14 from which the water gradually flows out as the return valve 16 does not offer resistance to such flowing.

In Figs. 2-4 details of preferred float and valve arrangements are shown. The floats consist in bottles 70, 170 of glass. The necks of the bottles are hermetically sealed by caps 123 which are pieced to the necks of the bottles by means of a cement. From said caps pins 124 are projecting which bear the valve cones 80 and 180 respectively. The float chambers consist of cylinders 40, 140 which enclose the floats 70 and 170 respectively and also the pipe 2^b with which the said chambers may be connected by soldering. The floats are guided on the interior surface of the cylinders 40 and 140 respectively and on the exterior surface of the pipe 2^b and also on the edges of ledges 70^b and 170^b respectively which are arranged in pairs and project in a radial direction from the walls towards the axis of the cylinders. The cylinder 40 is open on its lower side, and the cylinder 140 is open on its upper side.

The return valve of the upper chamber (Fig. 2) is not immediately adjacent to the bottom 20^b of the chamber, as shown in Fig. 1, but provided on the free end of a bent pipe 24 projecting from the bottom 20^b and communicating with the interior of the cylinder. The valve seat consists in a bushing 21^b which is screwed into the upwardly extending free end of the bent pipe 24, the said bushing being provided with three upwardly extending flaps 22 to which a hood 90^b is fastened which prevents the valve from being soiled. The hood is fastened to the flaps by means of screws 23 which also serve for limiting the stroke of the valve 16^b which consists of a thin and light disc of sheet metal for the reason of minimizing the quantity of gasoline remaining below the valve when filling the tank with water.

The return valve for the lower chamber 40 may be of a construction corresponding with that of Fig. 2. In this case the valve is also arranged to open upwards and preferably the valve should be provided on a reduced extension projecting upwardly from the upper wall 40^b of the chamber 40.

Instead of a return valve an orifice of small diameter such as a bore-hole 60 (Fig. 3) may be provided in the upper part of the wall of the chamber 40, such orifice connecting the interior of the tank 1 with the upper part of the interior of the chamber 40. The proper working of the lower float unit provided with said bore-hole depends on the following working conditions:

When filling up the storage tank with gasoline the corresponding sinking of the contacting plane between the gasoline and the water takes place quickly and without interruptions, whilst the rising of the contacting plane occurs at intervals due to the dispens-

ing of only smaller quantities of gasoline through a continuous drawing off and due to longer periods existing between the several dispensing operations. As soon as the sinking contacting plane has passed the bore 60, gasoline enters into the chamber 40. But as the bore is of a small diameter the said entering is so slow that after the contacting plane has reached the lower edge 50 of the chamber the latter is to a greater extent still filled with water so that the float 70 is still in its upper position. But as soon as the contacting plane passes the edge 50 the water falls out of the chamber 40 so that the valve 15 is suddenly closed. The effect is practically the same as with a return valve. When the contacting plane is rising it may occur that the entering of the water into the chamber from below is retarded in comparison with 20 the rising of the contacting plane, as the flowing out of the gasoline through the small bore cannot take place with a corresponding velocity. But this is unobjectionable as in the periods between the several dispensing 25 operations the difference in the levels is compensated and an immediate rising of the float is not of importance.

The bore 60 instead of a return valve may only be used for the lower float and valve 30 unit in view of the periods between the several dispensing operations and the possibility of compensation within such periods. With the bore 60 the construction is much simplified. This is also the case with the 35 other features shown in the Figs. 2 to 4, especially with the structure of the float chambers, the means for guiding the floats and especially with the floats proper. Floats consisting of bottles of glass are simple and cheap 40 and always air- and water-tight which is of great importance for a constant and reliable function of the floats.

The invention is not limited to the storing and dispensing of gasoline or similar liquid 45 fuels but may be employed in all cases in which liquids of different specific weight are stored in a single tank and are alternatively supplied to the tank and discharged from the same.

50 I claim:—

1. In a liquid storing and dispensing apparatus a tank, a heavier liquid conduit, communicating with the lower end thereof, a conduit for a lighter liquid, communicating 55 with the upper end of the tank, a valve for closing each of said conduits, a float for actuating each of said valves, an upper chamber and a lower chamber, for enclosing said floats, said upper chamber being open at the upper end thereof and provided with an outwardly opening check valve at the closed lower end thereof and said lower chamber being open at the lower end thereof and provided with an outwardly opening check valve 60 at the closed upper end thereof, whereby the

heavier liquid may reach the upper end of the upper chamber and said lighter liquid may reach the lower end of said lower chamber before said conduits are closed by said valves, thereby utilizing to the utmost the capacity 70 of said tank.

2. In a liquid storing and dispensing apparatus a tank, a heavier liquid conduit, communicating with the lower end thereof, a conduit of a lighter liquid, communicating with the upper end of said tank, a valve for closing each of said conduits, a float for actuating each of said valves, an upper chamber and a lower chamber, for enclosing said floats, said upper chamber being open at the upper end thereof and provided at the lower end thereof with a means for preventing the ingress and permitting the outflow of liquid therethrough, and said lower chamber being open at the bottom thereof and provided at the upper end thereof with a means for preventing the ingress and permitting the outflow of liquid therethrough, whereby the heavier liquid may reach the upper end of said upper chamber and said lighter liquid 80 may reach the lower end of said lower chamber before said conduits are closed by said valves, thereby utilizing to the utmost the capacity 85 of said tank.

3. In a liquid storing and dispensing apparatus a tank, a heavier liquid conduit, communicating with the lower end thereof, a conduit for a lighter liquid, communicating with the upper end of said tank, a valve for closing each of said conduits, a float for actuating each of said valves, an upper chamber and a lower chamber, for enclosing said floats, said upper chamber being open at the upper end thereof and provided with a means for causing the enclosed float to actuate its valve by the overflow of the heavier liquid over the upper end of said upper chamber thereinto, and said lower chamber being open at the lower end thereof and provided with a means for causing the enclosed float to actuate its valve by the underflow of the lighter liquid under the lower end of said lower chamber thereinto, whereby the heavier liquid may reach the upper end of said upper chamber and said lighter liquid may reach the lower end of said lower chamber before said conduits are closed by said valves, thereby utilizing to the utmost the capacity 90 of said tank.

4. In a liquid storing and dispensing apparatus a tank, a heavier liquid conduit, communicating with the lower end thereof, a conduit for a lighter liquid, communicating with the upper end of said tank, a valve for closing each of said conduits, a float for actuating the valve at said upper conduit, a chamber for enclosing said float, said chamber being open at the upper end thereof and provided with a means for causing said float to actuate said valve by the overflow of the heavier liquid over the upper end of said chamber thereinto, 125

- whereby the heavier liquid may reach the upper end of said upper chamber, before said upper conduit is closed by its valve, thereby utilizing to a greater extent the capacity of said tank.
5. In a liquid storing and dispensing apparatus a tank, a heavier liquid conduit, communicating with the lower end thereof, a conduit for a lighter liquid, communicating with the upper end of said tank, a valve for closing each of said conduits, a float for actuating the valve at said heavier liquid conduit, a chamber for enclosing said float, said chamber being open at the lower end thereof and provided with a means for causing said float to actuate said valve by the underflow of said lighter liquid under the lower end of said chamber thereinto, whereby said lighter liquid may reach the lower end of said chamber before said heavier liquid conduit is closed by said valve, thereby utilizing to a greater extent the capacity of said tank.
6. In a liquid storing and dispensing apparatus a tank, a heavier liquid conduit, communicating with the lower end thereof, a conduit for a lighter liquid, communicating with the upper end of said tank, a valve for closing each of said conduits, a float for actuating the valve at said heavier liquid conduit, a chamber for enclosing said float, said chamber being open at the lower end thereof and provided with an outwardly opening check valve at the closed upper end thereof, whereby said lighter liquid may reach the lower end of said chamber before said heavier liquid conduit is closed by said valve, thereby utilizing to a greater extent the capacity of said tank, and a hood positioned at the upper end of said chamber over said check valve, to limit the stroke thereof and to prevent solids, which may be suspended in the liquids, from interfering with the action of said check valve.
7. In a liquid storing and dispensing apparatus a tank, a heavier liquid conduit, communicating with the lower end thereof, a conduit for a lighter liquid, communicating with the upper end of said tank, a valve for closing each of said conduits, a float for actuating the valve at said upper conduit, a chamber for enclosing said float, said chamber being open at the upper end thereof and provided at the closed lower end thereof with an outwardly opening check valve, whereby the heavier liquid may reach the upper end of said chamber before said upper conduit is closed by its valve, thereby utilizing to a greater extent the capacity of said tank, and an extension on the walls of said chamber at the lower end thereof for encasing said check valve thereby shielding the same from impurities, which may be suspended in the liquids.
8. In a liquid storing and dispensing apparatus a tank, a heavier liquid conduit, communicating with the bottom thereof, a conduit for a lighter liquid communicating with the top of the tank, a valve for closing each of said conduits, a float for actuating each of said valves, an upper chamber and a lower chamber, for enclosing said floats, an opening in said upper chamber and an outwardly opening check valve at the lower end thereof, an opening in said lower chamber and an outwardly opening check valve at the upper end thereof, whereby the heavier liquid may reach the opening in said upper chamber and said lighter liquid may reach the opening in said lower chamber before said conduits are closed by said valves, thereby utilizing to a greater extent the capacity of said tank.
9. In a liquid storing and dispensing apparatus a tank, a heavier liquid conduit, communicating with the lower end thereof, a conduit for a lighter liquid, communicating with the upper end of said tank, a valve for closing each of said conduits, a float for actuating the valve of said heavier liquid conduit, a chamber for enclosing said float, an opening in said chamber and an outwardly opening check valve at the closed upper end of said chamber, whereby said lighter liquid may reach said opening before said heavier liquid conduit is closed by its valve, thereby utilizing to a greater extent the capacity of said tank.
10. In a liquid storing and dispensing apparatus, a tank, a heavier liquid conduit, communicating with the lower end thereof, a conduit for a lighter liquid, communicating with the upper end of said tank, a valve for closing each of said conduits, a float for actuating the valve at said upper conduit, a chamber for enclosing said float, an opening in said chamber and an outwardly opening check valve at the closed lower end of said chamber, whereby the heavier liquid may reach said opening before said upper conduit is closed by its valve, thereby utilizing to a greater extent the capacity of said tank.
11. In a liquid storing and dispensing apparatus a tank, a heavier liquid conduit, communicating with the lower end thereof, a conduit for a lighter liquid, communicating with the upper end of said tank, a valve, for closing each of said conduits, a float for actuating each of said valves, an upper chamber and a lower chamber, for enclosing said floats, one or more of said chambers being secured to said heavier liquid conduit, thereby supporting said chambers in position in said tank.
12. In a liquid storing and dispensing apparatus a tank, a heavier liquid conduit, communicating with the lower end thereof, a conduit for a lighter liquid, communicating with the upper end of said tank, a valve for closing each of said conduits, a float, for actuating each of said valves, an upper chamber and a lower chamber, for enclosing said floats, one or more of said chambers being secured to said heavier liquid conduit, thereby supporting said chambers in position in said tank.

- secured to said heavier liquid conduit, thereby supporting said chambers in position, and said heavier liquid conduit extending through one or more of said chambers, to assist in 5 guiding said floats therein.
13. In a liquid storing and dispensing apparatus a tank, a heavier liquid conduit communicating with the lower end thereof, a conduit for a lighter liquid, communicating with the upper end of said tank, a valve, for closing each of said conduits, a float for actuating each of said valves, an upper chamber and a lower chamber, for enclosing said floats, said upper chamber being open at the upper 10 end thereof and provided at the closed lower end thereof with a bent pipe of reduced size, in communication therewith, said pipe terminating in an outwardly opening check valve, whereby the heavier liquid may reach above the open end of said upper chamber before 15 the conduit of said lighter liquid is closed by its valve.
14. In a liquid storing and dispensing apparatus a tank, a heavier liquid conduit, communicating with the lower end thereof, a conduit for a lighter liquid, communicating with the upper end of said tank, a valve, for closing each of said conduits, a float for actuating each of said valves, an upper chamber 20 and a lower chamber, for enclosing said floats, said upper chamber being open at the upper end thereof and provided at the closed lower end thereof with a passage of a reduced size, in communication therewith, said passage 25 terminating in an outwardly opening check valve, whereby the heavier liquid may reach above the open end of said upper chamber before the conduit of said lighter liquid is closed by its valve.
15. In a liquid storing and dispensing apparatus a tank, a heavier liquid conduit, communicating with the lower end thereof, a conduit for a lighter liquid, communicating with the upper end of said tank, a valve, for 30 closing each of said conduits, a float, for actuating each of said valves, an upper chamber and a lower chamber, for enclosing said floats, one or more of said chambers being secured to said heavier liquid conduit, thereby 35 supporting said chambers in position, one or more of said chambers having thereon guides for said floats, and said heavier liquid conduit extending through one or more of said chambers, to assist in guiding said floats 40 therein.
16. In a liquid storing and dispensing apparatus a tank, a heavier liquid conduit, communicating with the lower end thereof, a conduit for a lighter liquid, communicating with the upper end of said tank, a valve, for closing each of said conduits, a float, for actuating each of said valves, an upper chamber and a lower chamber for enclosing said floats, one or more of said floats comprising a hollow 45 main body of glass, a cap, cemented to said 50 body and a means on said cap for connecting the same to a valve, for actuating the same.
17. In a liquid storing and dispensing apparatus a tank, a heavier liquid conduit, communicating with the lower end thereof, a conduit for a lighter liquid, communicating with the upper end of the tank, a valve, for closing each of said conduits, a float, for actuating each of said valves, an upper chamber and a lower chamber, for enclosing said floats, and a means on one or more of said chambers to permit one of said liquids to pass the remote end of the float chamber, controlling the admission of the other liquid, before the conduit of the latter liquid is closed, thereby utilizing to a greater extent the capacity 55 of said tank.
18. In a liquid storing and dispensing apparatus a tank, a heavier liquid conduit, communicating with the lower end thereof, a conduit for a lighter liquid, communicating with the upper end of said tank, a valve, for closing each of said conduits, a float, for actuating each of said valves, an upper chamber and a lower chamber, for enclosing said floats, 60 said upper chamber being open at the upper end thereof and provided at the closed lower end thereof with an outwardly opening check valve, and said lower chamber being open at the lower end thereof and provided at the upper end thereof with a means for preventing the inrush of liquid thereinto and permitting the outflow of liquid therefrom.
